UNITED STATES PATENT OFFICE.

JAMES EAGEN, OF WYOMING, PENNSYLVANIA.

COAL OR ROCK DRILL.

SPECIFICATION forming part of Letters Patent No. 659,139, dated October 2, 1900.

Application filed July 8, 1898. Renewed March 15, 1900. Serial No. 8,856. (No model.)

To all whom it may concern:

Be it known that I, JAMES EAGEN, a citizen of the United States, residing at Wyoming, in the county of Luzerne and State of Pennsylvania, have invented certain new and useful Improvements in Coal or Rock Drills; and I do declare the following to be a full, clear, and exact description of the invention, such as will enable others skilled in the art to which it appertains to make and use the same, reference being had to the accompanying drawings, and to the figures of reference marked thereon, which form a part of this specification.

5 My invention relates to coal and rock drills, particularly to the drill and bit used in drilling-machines in which the stem or shank of the drill is screw-threaded and works through a nut movably secured to the support.

10 The invention consists in the connection (which is an improvement on Patent No. 328,495 by James S. Loftus and which is now owned by myself) and in the cutter or bit and means of securing the same to the extension-bar.

15 Reference is to be had to the accompanying drawings, which form a part of this specification, and in which like numerals of reference refer to like parts in the different figures.

20 Figure 1 is an elevation of the drill and bit. Fig. 2 is an end view or plan of the bit. Fig. 3 is a side view or elevation of the bit. Fig. 4 is a view of the male end of the connection. Fig. 5 is a view of the connection, the dotted lines indicating the interior of the socket and the male end of the connection in place in the socket. Fig. 6 is an elevation of the front of the socket with male end in position, the dotted lines indicating the interior. Fig. 7 is a cross-section of the end of the extension-bar with bit in place, showing the method of holding the bit in place. Fig. 8 is an elevation of the end of the drill or extension-bar where the bit is secured. Fig. 9 25 represents two edge elevations of the cutting end of the bit, the dotted lines showing the oppositely-inclined planes of the two bevels.

30 1 is the drill, 2 the male end of the connection, and 3 the slot in the socket to receive the pin 5, which is secured to the male end of the connection.

35 4 is an elongation or enlargement of the

slot at its lower end to prevent the breaking strain on the pin after the socket and male end of the connection have become somewhat 55 worn by use.

60 6 is the reverse-curve bit; 7, the shank of the bit; 8, the point of curvature; 9, the point of reverse curvature, and 10 the hole in the shank of the bit to receive the bolt 12, which 65 passes through the hole 10 in the bit and the hole 11 in the end of the drill, being held rigidly in place by the nut 13.

70 14 is the flattened end of the drill or extension-bar 1, with its edges turned over to form 65 the lips 15, under which the shank of the bit 7 passes.

75 The manner of connecting the drill, so as to form any desired length of convenient lengthened pieces, I do not claim as new. 70 My improvement is one, however, which has made itself manifest by experience with the above-noted patent, which I now own. It has been demonstrated that after some use the socket and also the male end of the connection become worn, so that the pin 5 is subjected to a breaking strain which causes a great deal of trouble and inconvenience when the drill is withdrawn from the hole. This trouble I obviate by the elongation or 80 enlargement 4 of the slot 3 at its lower end at the position of the pin when the male end of the connection is at its proper position in the socket.

85 The cutter or bit I make in the form of a reverse curve or partial S shape in cross-section, having its point of reverse curvature at or near the center of said bit. The cutting edge is formed by beveling off the bit half on one side and half on the other side, each 90 bevel taking in one of the convexed portions formed by the S shape of the bit, whereby the two beveled portions will meet at the center of the cutting edge—that is, at the point of the reverse curvature—and form a central 95 entering-point 9 and two entering and cutting points 8 at the edges of the bit, giving the cutting edge an escalloped form in side elevation. It will be observed that a bit of this form may be sharpened readily and without other tools than a file, the bit lasting until it is entirely used up. My object is to 100 overcome an existing source of trouble in the ordinary form of coal and rock drills—i. e.,

73 74 75 76 77 78 79 80 81 82 83 84 85 86 87 88 89 90 91 92 93 94 95 96 97 98 99 100

the necessity of having a blacksmith to sharpen the bit or cutter, which is a source of expense to the miner; also, the keeping of the cutter or bit in its proper shape when sharpened with a file by the operator, (a difficult matter for a miner unskilled in the use of tools.) By using the reverse-curve bit or cutter it is only necessary to file it from each side, filing each time from the convex side, 10 as the center of the bit is necessarily at the point of reverse curvature, and the outer edge of the bit will be brought to a point, thus saving the blacksmith's charge for sharpening and giving a bit whose cutting qualities 15 are far in excess of the other styles now employed.

An essential feature lies in the fact that each bevel cuts straight across and is coextensive with one of the two convexed portions, 20 the two bevels meeting at the center and their planes being oppositely inclined to the axis of the bit, as shown most clearly by the dotted lines in Fig. 9. This enables a common flat file or flat-faced grinding-wheel to be used for 25 sharpening the bit, no careful manipulation of the file or the bit being required.

The socket to hold the bit I make by flattening one end of the extension-bar of the drill and turning its edges over to form the

lips 15, as shown in Figs. 7 and 8, thus forming a rigid socket, one which may be readily cleaned, also one from which the bit may be readily withdrawn after the bolt has been removed, and also one in which force may be readily used in case it is necessary in the removal of the bit.

Having thus fully described my invention, what I claim as new, and wish to secure by Letters Patent, is—

A bit for coal and rock drills, consisting of 40 a body portion substantially S shape in cross-section, its cutting edge being formed by two bevels, each bevel being coextensive with and cutting straight across one of the two convexed portions of the body portion, the two 45 bevels being upon opposite sides of the bit and being oppositely inclined and meeting at the axial center of the bit, whereby three entering and cutting points are formed, one midway the cutting edge and one at each end 50 thereof, for the purposes set forth.

In testimony whereof I affix my signature in presence of two witnesses.

JAMES EAGEN.
